[57] CLAIM

The ornamental design for a venturi wall for wet separators and the like, substantially as shown and described.

DESCRIPTION

FIG. 1 is a front end elevation of a venturi wall for wet separators and the like embodying our design;
FIG. 2 is a rear elevation of the venturi wall shown in FIG. 1;

FIG. 3 is a top plan view of the venturi wall as seen from above in FIG. 1;

FIG. 4 is a bottom plan view of the venturi wall as seen from the bottom in FIG. 2; and

FIG. 5 is a side elevation of the wall as seen from the left hand side of FIG. 1.

The fragmentary broken line showing of support structure in FIGS. 1 through 5 is for purposes of illustration only.
